CLAIM

The ornamental design for a portable information handling system, as shown and described.

DESCRIPTION

FIG. 1 is a front perspective view of the portable information handling system comprising the present invention;

FIG. 2 is a front view thereof;

FIG. 3 is a right side view thereof;

FIG. 4 is a left side view thereof;

FIG. 5 is a top view thereof with the lid shown closed;

FIG. 6 is a top view thereof with the lid shown open; and,

FIG. 7 is a bottom view thereof.

Broken lines shown in the drawings illustrate portions of the portable information handling system, and form no part of the claimed design.
